CLAIM

The ornamental design for a combined golf green repair tool and holder for ball marker, as shown and described.

DESCRIPTION

FIG. 1 is a front elevational view of a combined golf green repair tool and holder for ball marker, showing my new design, the broken line showing of a coin or a disc ball marker is for illustrative purposes only, and forms no part of the claimed design;

FIG. 2 is a rear elevational view thereof;

FIG. 3 is a front, top, right perspective view thereof, the left side being a mirror image; and,

FIG. 4 is a front, lower right perspective view thereof, the left side being a mirror image.

The shape of the tool, when viewed from the upper left and lower left in FIG. 1, is similar in appearance to that shown in FIGS. 3 and 4, respectively. The broken line showing in FIG. 1 illustrates a coin or disc ball marker adapted to be removably carried by the tool.
